UNITED STATES PATENT OFFICE.

WINTHROP W. BENNER, OF CUYAHOGA FALLS, AND EDMUND A. HOENER, OF AKRON, OHIO, ASSIGNORS TO THE FIRESTONE TIRE AND RUBBER COMPANY, OF AKRON, OHIO, A CORPORATION OF OHIO.

APPARATUS FOR SPLICING FABRIC.

Application filed December 5, 1922. Serial No. 605,058.

This invention relates to a method and apparatus for splicing or joining together the ends of fabric or other material, and while it may have varied and different uses, it is primarily intended for use in joining together ends of fabric rolls such as are used in the manufacture of pneumatic tires, and especially for use in conjunction with a continuous calendering operation described and claimed in our copending application Serial No. 638,497, filed May 12, 1923.

Heretofore it has been proposed to unite the leading end of a roll of fabric to the last end of another roll of fabric by stitching or sewing them together, but this operation has not been altogether satisfactory, and it is the purpose of this invention to provide a simpler and more efficient method of uniting the ends of the fabric.

In the particular application of the invention it is the object to form the fabric in a continuous strip or web which is led, without interruption, through a series of calenders which apply the various coatings of rubber thereto, so that the operation may go on continuously, thereby obtaining a more efficient calendering unit.

In the drawings accompanying this application is shown one type of apparatus, and the description gives a preferred sequence of steps for carrying out the method, but changes and modifications may be made in both aspects of the invention within the scope of the claims attached hereto.

In the drawings:

Figure 1 shows a side elevation of an apparatus for carrying out the splicing operation;

Figure 2 is a plan view;

Figure 3 is an end elevation looking from the left-hand end of Figure 1;

Figure 4 is a vertical section through the splicing mechanism showing the device in closed position;

Figure 5 is a fragmentary plan thereof; and

Figures 6 and 7 illustrate two steps in the method of forming the splice.

As stated in the earlier portion of the specification, it is the object of the invention to provide a method and means by which the leading end of a fresh roll of fabric may be secured to the last end of a nearly exhausted roll so that a continuous calendering

operation may be carried on without interruption.

In the drawings, the approximately exhausted roll of fabric is indicated by the letter A and the fresh roll by the letter B. The roll of fabric A from which the calenders have been drawing the fabric toward the right of Figure 1, is supported in a cradle 1, provided with a plurality of supporting rollers 2, so that the fabric roll will easily unwind. The path of the fabric is shown by the dot and dash lines marked *a* and is from the roll, over guide roller 3 supported in framework 4 and over guide roller 5 in bracket 6, thence through a pair of smoothing and tensioning rollers 7 to the dance rolls and calenders not shown. One of the rollers 7 may be provided with a brake drum 8 which is for the purpose of exerting a proper tension on the fabric so that it will not overrun itself and will not be drawn back after leaving the rolls.

The fresh roll of fabric B is supported in a cradle composed of rollers 9 which are mounted in a pivoted frame 10. The frame 10 is pivotally mounted on a transverse shaft 11 which is slightly off-center so that the tendency of the frame is to tip downwardly toward the cradle 1. The shaft 11 is supported in a carriage 12 and the cradle is locked in elevated position by a pin 13 (Figure 2). When the pin 13 is released the cradle 9 will drop to discharge the roll into the cradle 1. Lugs 14 in the pivoted frame contact the upper surface of the carriage and prevent accidental tipping of the cradle in the opposite direction.

The carriage 12 is supported on rollers 15 which run on transverse tracks 16 so that the carriage may be moved to one side to have the new roller placed in position.

On the opposite side of the carriage is arranged a cutting and folding table 17, the purpose of which will be described later.

At the extreme left of the apparatus, as viewed in Figure 1, is the splicing device, indicated in general by the numeral 18. This comprises two vertical uprights 19 connected by two cross pieces 20. On the lower inside surfaces of the uprights 19 are arranged vertical guideways 21 in which is slidably mounted a horizontal cross-bar 22. This cross-bar is arranged to be raised and lowered by a rock shaft 23 mounted in bear-

ings 24 on the lower cross-bar 20 and carrying arms 25 which are connected to the bar 22 by links 26. An operating lever 27 is attached to the arm so that by manipulation of the lever, the cross-bar may be raised and lowered. On the upper surface of the cross-bar is supported a table 28 which extends to the rear of the standards and which is provided at its forward end with a sheet metal trough 29 which extends the length of the table. A padding 30 may be inserted within the trough if desired.

Above the trough 29 is supported by straps 31 a horizontal stationary heated pipe 32. The splicing device is adapted to be used in securing together the ends of the fabric rolls by a vulcanized splice as will be understood as the method is described.

The method of using the apparatus and of forming the union between the ends of the fabric is substantially as follows:

As the roll A nears exhaustion, the operators pull from it, at a more rapid rate than the speed of the calenders, the remainder of the roll of fabric and pile it in folds as shown at C. The fresh roll of fabric B being in position, the last end of the roll A is carried back to the cutting and folding table 17 and may be cut off square by the aid of a ruler 33. The leading end of the roll B is also brought back to the table 17 and folded over a straight edge 34 so as to obtain a square joint. The folded portion of the roll is indicated by the letter b and the last end of roller A by the letter a' in Figure 7. Between these portions of the fabric is placed a thin strip of uncured, quick vulcanizing rubber d and the ends of the fabric are laid in the trough 29, which is lowered for that purpose as shown in Figure 3. The lever 27 is now operated and the trough raised until the superposed ends of the fabric contact with the heated pipe 32 in which position they are held until the rubber is cured, which joins the ends of the fabric together. The composition of the rubber strip d is such that a few moments will suffice for curing the splice whereupon the cross-bar is lowered and the fabric can be conducted through the calender train as a continuous piece.

The cradle 9 is now tilted downwardly and the fabric rolls into the trough 1. The calenders soon take up whatever slack remains after the splicing operation and a new roll is placed in the cradle 9, the operations described being repeated indefinitely during the operation of the system.

The description has been given with sufficient detail so as to enable one skilled in

the art to practice the invention, but it will be understood that such details are not important and may be changed or modified as desired within the scope of the attached claims.

What we claim is:

1. An apparatus for uniting the ends of fabric rolls into a continuous web, comprising supports for the exhausted and the fresh rolls, a vulcanizing apparatus adjacent the supports, and means for removing the fresh roll and placing it in the position of the exhausted roll.

2. An apparatus for uniting the ends of fabric rolls into a continuous web, comprising a stationary cradle for the exhausted roll and a tilting cradle for the fresh roll above the other cradle, an apparatus for uniting the ends of the fabric rolls, and means for tilting the cradle to discharge the fresh roll into the stationary cradle.

3. An apparatus for uniting the ends of fabric rolls into a continuous web, comprising a cradle for the exhausted roll and a cradle for the fresh roll, an apparatus for uniting the ends of the fabric rolls, and means for discharging the fresh roll into the cradle for the exhausted roll.

4. An apparatus for uniting the ends of fabric rolls into a continuous web, comprising a support for the exhausted roll and a support for the fresh roll, an apparatus for uniting the ends of the rolls into a continuous web, and means for transferring the fresh roll into the place of the exhausted roll after the ends have been united.

5. An apparatus for the uses and purposes set forth, comprising a support for an exhausted roll of fabric and a support for a fresh roll of fabric, a vulcanizing press for uniting the ends of the fabric by a vulcanizing operation, and means for moving the fresh roll of fabric to the position for the exhausted roll after the fabric ends have been vulcanized together.

6. An apparatus for the uses and purposes set forth, comprising a support for an exhausted roll of fabric and a support for a fresh roll of fabric, means for uniting the ends of the fabric by vulcanization comprising a heated element and a complementary member and means for moving said element and member together to cure the union between the ends of the fabric, and means for moving the fresh fabric roll to the position for the exhausted roll after the fabric ends have been vulcanized together.
